DESIGN FOR A SHOE STAND

Frank C. Castelli, Carroll Park, and Herman
Kesler, Philadelphia, Pa.

Application May 29, 1940, Serial No. 92,675

Term of patent 7 years

To all whom it may concern:

Be it known that we, Frank C. Castelli and Herman Kesler, citizens of the United States and residents, respectively, of Carroll Park, in the county of Montgomery and State of Pennsylvania, and Philadelphia, in the county of Philadelphia and State of Pennsylvania, have invented a new, original, and ornamental Design for a Shoe Stand, of which the following is a specification, reference being had to the accompanying drawing, forming a part thereof.

In the drawing:

Fig. 1 is a perspective view of a shoe stand, showing our new design; and

Fig. 2 is an enlarged fragmentary perspective view, partially in section, of a joint element thereof taken at the line 2—2 of Fig. 1.

We claim:

The ornamental design for a shoe stand, as shown.

FRANK C. CASTELLI.
HERMAN KESLER.
